ANDREW KULL, JR., OF BLOOMFIELD, WISCONSIN.

Letters Patent No. 96,814, dated November 16, 1869.

IMPROVEMENT IN FENCE.

The Schedule referred to in these Letters Patent and making part of the same.

To all whom it may concern:

Be it known that I, ANDREW KULL, Jr., of the town of Bloomfield, county of Walworth, and State of Wisconsin, have invented a new and useful Improvement in Fences; and I do hereby declare that the following is a full, clear, and exact description thereof, which will enable those skilled in the art to make and use the same, reference being had to the accompanying drawing, forming part of this specification, in which—

Similar letters of reference in each of the figures indicate corresponding parts.

The object of my invention is to produce a fence easily put together, strong, and reliable.

A are the boards lengthwise.

B, the side-braces and supports, chamfered at their ends.

C, a foot-piece that the posts and supports may stand on when the foot-piece is used, which it may or may not be, as desired.

D, the posts, through slots in the upper ends of which the side-braces pass at their upper end, the end passing through the post, and catching under the upper boards A, holding the fence firmly in position.

In putting up this fence, slots are made in all the posts, same as shown in the two, in the drawings where the side-braces are. Put the side-braces in, as shown in fig. 1, and jam the fence-posts and side-braces into the ground, and the fence is secure; or if the ground is very soft, use the bottom piece C, as shown, fig. 2. This is a very firm fence, and one quickly made.

What I claim as my invention, and desire to secure by Letters Patent, is—

A fence, when constructed with parts A, B, and D, the parts B and D forced into the ground, substantially as described.
